UNITED STATES PATENT OFFICE.

GEORGE SKEFFINGTON MILNE GRIMMER, OF LONDON, ENGLAND.

PENCIL OR LIKE HOLDER.

Application filed March 21, 1928, Serial No. 263,260, and in Great Britain August 17, 1927.

This invention is for improvements in or relating to pencil or like holders of the type wherein the point of the lead can be sharpened by moving the latter axially between sharpening members that are resiliently attached to the pencil-holder. In one known construction of this type, the sharpening members consist of two serrated, file-like, or otherwise roughened, jaws, carried by converging spring strips, which jaws operate on the lead as it is rotated in and out of the holder by the propelling mechanism.

One object of the present invention is to provide an improved device of the aforesaid type, in one form of which a "chisel-point" can be produced on the lead, such as is commonly used by draughtsmen in making engineering or other drawings.

According to one feature of the present invention, in a pencil or like holder, of the type referred to, the lead is mounted in a spring-controlled carrier (e. g. a plunger) slidably arranged in the holder in such a manner as to permit of the lead being moved inwardly between the sharpening members which are in the form of chisel-edge cutters (against the action of the spring) by the application of pressure to the point of the lead and being moved outwardly between said members by the spring when the pressure is released.

The term "chisel-edge cutters" herein is intended to include cutters having either a straight or curved continuous cutting-edge as distinguished from sharpening members having file-like cutting surfaces.

Conveniently, the lead-carrier is slideable within a guide which is so arranged within the holder as to be adjustable along it to vary the normal position of the lead-carrier in relation to the holder.

According to another feature of the invention, there is provided in a pencil or like holder, according to either of the last two preceding paragraphs, a device movable with the lead-carrier and co-operating with the sharpening members to cam the latter on to the lead at each cutting stroke.

The invention also comprises means (for example, a fixed pin co-acting with a cam-groove on the lead-carrier) for producing a partial rotary movement of the lead-carrier during its axial movement in one or both directions, or between successive axial movements.

According to a further feature of the invention, means are provided whereby the lead

can be locked in its operative position, for example, a cap adapted to press the sharpening members inwardly sufficiently to grip the lead.

The invention also includes a pencil or like holder, of the type described, wherein the sharpening members have chisel edges and the lead is mounted for reciprocation between said edges in a carrier so arranged that the lead is constrained against rotational movement in relation to the edges aforesaid so as to produce a "chisel-point" on the lead.

For a more complete understanding of the invention, several constructions in accordance therewith will now be described by way of example with reference to the accompanying drawings, in which—

Figure 1 is a sectional elevation of one embodiment of the invention;

Figure 2 is a plan thereof;

Figure 3 is a sectional elevation of a modification;

Figure 4 is a plan of the latter;

Figure 5 is an elevation, partly in section, of another modification;

Fig. 5^a is a view showing the development of the cam groove shown in Fig. 5.

Figure 6 is a sectional elevation of still another modification;

Figure 7 is a plan, partly in section, of the latter modification;

Figure 8 is a section on the line 8—8 of Figure 6, and

Figure 9 is a perspective view of the lead-carrier employed in the construction shown in Figure 6.

Like reference numerals indicate like parts in the several views of the drawings.

The pencil-holder shown in Figures 1 and 2 comprises a hollow cylindrical body 10 of metal, or other suitable material. This body part is closed at one end by a screw-cap 11, and at the other end by a hollow conical end-piece 12, through which the lead 13 normally projects.

The lead 13 is mounted in a stationary guide-member 23, and the inner end of the lead is received in a lead-carrier 14 provided with a collar 15.

Between said collar and the cap 11, a spring 16 is arranged. The lead-carrier is mounted in a guide 17 which can be adjusted axially of the pencil-holder by means of a screw 18, engaging a slot 19 in the holder, so that by adjusting said guide along the pencil-holder, the amount of exposed lead can be varied at will.

Mounted on the end-piece 12 are two spring sharpen-

ing-blades 20 which press against the lead beyond the outer extremity of the end-piece 12. These blades are arranged diametrically opposite to one another and are provided 5 with chisel-like sharpening edges of a width not less than the diameter of the lead.

The action of the device is as follows. The lead-carrier is adjusted so as to expose the desired length of lead, and the pencil-holder 10 is held with the point of the lead against some solid object, for example, a table, and pressed against the action of the spring 16, during which operation the sharpening-blades 20 remove a portion of the lead. The pressure 15 is then released, and the lead returns to its normal position under the action of said spring. This operation is repeated until a chisel-point of the desired sharpness has been obtained.

20 In the construction shown in Figures 3 and 4, the guide 17 is fixed in a tubular-member 21 by a pin 22. The tubular-member 21 is screwed into one end of the body part 10 so that the length of exposed lead can be ad- 25 justed by screwing the member 21 in or out of the part 10. The guide-member 23 for the lead is screwed into the other end of the body part 10, and the spring sharpening-blades 20 are mounted on said guide-member. Slid- 30 ably mounted on the body part 10 is a cap 24, having a conical outer end 25, provided with two slots 26 to accommodate the sharpening blades 20. A spring 27 is disposed between a shoulder 28 on the guide-member 23, and a 35 stop 29 on the interior of the cap 24. A pin 30 mounted in the guide-member 23, projects into a guide-slot 31 in the cap 24.

In the foregoing construction, when pres- 40 sure is applied to the pointed end of the lead, the latter is moved backwardly against the action of the spring 16 until the point of the lead is level with the outer end of the cap 24. Continued pressure then causes the said cap to slide backwardly over the body part 10, 45 against the action of the spring 27, and this movement of the cap causes the latter to press the sharpening blades 20 against the lead with a cam-like action and with a pressure which increases as the lead moves inwardly. 50 When the external pressure is released, the parts return to their normal positions under the action of their respective springs 16 and 27.

55 Both these specific constructions hereinbefore described produce a chisel-point on the lead as the latter has only an axial movement within the holder. In the modification shown in Figure 5, the pin 22 extends into a cam-groove 32 in the lead-carrier 14. This 60 cam-groove which extends circumferentially of the lead-carrier is of zig-zag formation and is so shaped that at each bend thereof the apical point at one side of the groove is off-set relatively to the corresponding recess at 65 the other side of the cam-groove. Each

apical point on each side of the groove is joined to the adjacent recess by a substan- 70 tially straight portion, so that each side of the groove presents a number of sub- 75 stantially triangular-shaped teeth. When the lead-carrier is at the end of its for- 75 ward stroke, the pin 22 is in engagement with one of the recesses in the rear side of the groove, so that the lead-carrier is not rotated during its rearward movement until, by rea- 80 son of the aforesaid off-set arrangement, said pin engages the other side of the cam-groove on one side of the apical point thereon corre- 85 sponding to the recess in which the pin was seated prior to this movement. The pin then turns the lead-carrier through an angle de- 90 termined by the slope of the aforesaid sub- 95 stantially straight portion and the length thereof engaged by said pin. When the lead- 100 carrier has completed its rearward stroke, the pin 22 is seated in one of the recesses in the forward side of the zig-zag groove, and during the forward movement of the lead-car- 105 rier no rotation of the latter takes place until said pin engages a substantially straight por- 110 tion of the rear side of the groove. The lead- 115 carrier is then again rotated in the same direc- 120 tion as before. The cam-groove is so shaped that for every complete stroke of the lead- 125 carrier a given angular movement will be im- 130 parted to the lead and always in the same direction; thus, there is a certain amount of lost motion while the pin is passing from one portion of the groove to the next, and the lead-carrier 14 is partially rotated only at the end of each stroke. By this means a round point is produced on the lead.

Referring now to the construction shown in Figures 6-9, inclusive, the pencil-holder comprises a main body part 10, a tubular- 105 member 21, a sleeve 33, and a cap 24. The tu- 110 bular-member 21 is rotatably mounted in the body part 10, and is operatively connected to the lead-carrier, for the purpose of ad- 115 vancing or retracting the lead within the holder, by means of a bar 34, which is slid- 120 ably mounted axially of the holder within a slot 35 in the inner end of the tubular-member 21, see Figure 8. The bar 34 is secured to a tubular-member 36, rotatably mounted in the body part 10, and provided with a quick-pitch 125 thread which co-acts with a pin 37 fixed in said body part. The tubular-member 36 constitutes a guide for the lead-carrier 14, which, in this construction, is formed in two parts, (see especially Figure 9), whereof one part is a sleeve 38 which is loosely mounted between two collars 39, 40 on the other part 41 of the lead-carrier with sufficient clearance to permit endwise movement.

The cap 24 is a sliding fit on the portion 42 of the body part 10, and the sleeve 33 sur- 130 rounds the cap 24. The sleeve 33 is provided on its interior surface with projections 43 adapted to co-act with projections 44 on the

periphery of the portion 42 to prevent longitudinal movement of the said sleeve. A pin 45 on the sleeve 33 extends into a slot in the cap 24, which slot comprises a longitudinal portion 46, a transverse portion 47, and a second transverse portion 48 communicating with a longitudinal portion 49, for the purpose hereinafter described. A pin 50, in the tubular-member 36, engages a helical groove 51, in the sleeve 38, and a tooth 52, on the shoulder 40, is adapted to engage ratchet-teeth 53 on the adjacent end of the sleeve 38. A spring 27 is arranged between a shoulder 28 on the guide-member 23 and a stop 29 on the interior of the cap 24.

The operation of this construction is as follows. The sleeve 33 is set so that an indicating line 54 thereon coincides with a setting line 55 on the body part 10 of the holder, in which position of said sleeve the pin 45 is located at the rear end of the longitudinal slot 46 in the cap 24. With the cap in this position, the lead 13 can be pressed back against the action of the spring 16, until it is level with the outer end of the cap 24, when continued pressure will cause the said cap to move backwardly against the action of the spring 27 and to press the blades 20 against the lead with an increasing pressure as the latter moves inwardly, thus removing a portion of the lead. During this stroke, the lead does not rotate as the tooth 52 is out of engagement with the ratchet-teeth 53. When the external pressure on the point of the lead is released, the cap 24 is caused to move forwardly by the spring 27, and the pressure of the blades 20 on the lead is relaxed. The lead-carrier 14 then moves forwardly under the action of the spring 16 and the tooth 52 is caused to engage the ratchet-teeth 53 with the result that the lead-carrier, and consequently the lead, will be partially rotated. The foregoing operations are then repeated for a sufficient number of times to produce a point of the desired sharpness. In order to lock the lead in position for writing, the cap 24 is depressed against the spring 27 until the sleeve 33 can be turned so that the pin 45 will engage the transverse slot 47, this position being indicated by the coincidence of the indicating line 54 with a setting line 56 on the body part 10. If it is desired to remove the cap 24 for refilling, or other purposes, the said cap is pressed inwardly against the spring 27 until the pin 45 can be turned to engage the end of the transverse slot 48 in alignment with the longitudinal slot 49, which position is indicated when the line 54 is coincident with the setting line 57. In this position, the cap 24 can be readily withdrawn from the holder. Obviously, the cap can be replaced by a reversal of the foregoing operations.

It is to be understood that the invention is not restricted to the precise constructional details described, as, obviously, several

changes can be made without departing from the invention.

I claim:

1. In a pencil or like holder of the type referred to, the combination of sharpening members in the form of chisel-edge cutters arranged about the lead near the forward end of the holder and a lead-carrier which is slidably arranged in the holder and controlled by a spring in such manner as to permit of the lead being moved inwardly between the sharpening members against the action of said spring by the application of pressure to the point of the lead and being moved outwardly between said members by the spring when the pressure is released.

2. A pencil or like holder of the type referred to, comprising in combination sharpening members in the form of chisel-edge cutters arranged about the lead near the forward end of the holder, a spring-controlled lead-carrier, a guide in which the lead-carrier is slidably mounted, and means whereby said guide can be adjusted along the holder to vary the normal position of the lead-carrier in relation to the holder.

3. In a pencil or like holder of the type referred to, the combination of sharpening members in the form of chisel-edge cutters arranged about the lead near the forward end of the holder, a lead-carrier, a guide-member for the lead at the front end of the holder, a guide in which the lead-carrier is slidably mounted, and a spring for urging the lead-carrier forwardly in the pencil holder, all so arranged as to permit of the lead being moved inwardly between the sharpening members by the application of pressure to the point of the lead and being moved outwardly between said members by said spring when the pressure is released so as to produce a chisel-like point on the lead by the reciprocation of the latter between the sharpening members.

4. In a pencil or like holder of the type referred to, the combination of sharpening members in the form of chisel-edge cutters arranged about the lead near the forward end of the holder, a lead-carrier which is slidably arranged in the holder and urged forwardly by a spring in such manner as to permit of the lead being moved inwardly between the sharpening members against the action of said spring by the application of pressure to the point of the lead and being moved outwardly between said members by the spring when the pressure is released, and means for forcing the sharpening members on to the lead at each cutting stroke.

5. In a pencil or like holder of the type referred to, the combination of sharpening members in the form of chisel-edge cutters arranged about the lead near the forward end of the holder, a lead-carrier which is slidably arranged in the holder and controlled by a

spring in such manner as to permit of the lead being moved inwardly between the sharpening members against the action of said spring by the application of pressure to 5 the point of the lead, and being moved outwardly between said members by the spring when the pressure is released, and a device movable with the lead-carrier and arranged to force the sharpening members on to the 10 lead at each cutting stroke.

6. A pencil or like holder of the type referred to, comprising in combination a spring-controlled reciprocatable lead-carrier mounted within the holder, a guide-member for the 15 lead at the front end of the holder, sharpening members in the form of spring-blades mounted on said guide-member, which spring-blades have at their forward ends chisel-edge cutting surfaces, a cap slidably mounted on 20 the body part of the holder and provided with a conical outer end, a shoulder on said guide-member, a stop on the interior of said cap, and a spring interposed between said shoulder and said stop, all arranged for operation 25 substantially as hereinbefore described.

7. A pencil or like holder according to claim 6, wherein the conical outer end of said cap is provided with slots to accommodate the sharpening members, and wherein means 30 are provided for preventing rotational movement of said cap in relation to the pencil holder.

8. In a pencil or like holder of the type referred to, the combination of sharpening 35 members in the form of chisel-edge cutters arranged about the lead near the forward end of the holder, a lead-carrier which is slidably arranged in the holder and controlled by a spring so as to permit of the lead being 40 moved inwardly between the sharpening members against the action of said spring by the application of pressure to the point of the lead and being moved outwardly between said members by the spring when the pressure is 45 released, and means for producing a rotary movement of the lead-carrier so as to produce a round point on the lead.

9. A pencil or like holder of the type referred to, comprising in combination sharpening members in the form of chisel-edge cutters arranged about the lead near the forward end of the holder, a lead-carrier reciprocatably mounted in said holder, a spring urging 50 said lead-carrier forwardly and so arranged 55 that the lead can be moved inwardly between the sharpening members against the action of the spring by the application of pressure to the point of the lead and will be moved outwardly between said members by the spring 60 when the pressure is released, a cam groove on the lead-carrier, and a pin fixed to the inner wall of said holder and projecting into 65 said cam groove for producing a rotary movement of the lead-carrier, which cam groove is so shaped that at the end of each complete

stroke of the lead carrier a given angular movement is imparted to the lead and always in the same direction so that the lead is rotated between successive axial movements.

10. In a pencil or like holder of the type referred to, the combination of sharpening members in the form of chisel-edge cutters arranged about the lead near the forward end of the holder, a lead-carrier slidably arranged in the holder and controlled by a spring in 75 such manner as to permit of the lead being moved inwardly between the sharpening members by the application of pressure to the point of the lead and being moved outwardly between said members by said spring 80 when the pressure is released, which lead-carrier is formed in two parts whereof one part is a sleeve loosely mounted between two collars on the other part, a cam groove on the outer surface of said sleeve co-operating with 85 a fixed pin to rotate said sleeve when it is reciprocated, and a clutch tooth on one of said collars adapted to engage clutch teeth on the adjacent end of said other part of the lead-carrier, all so constructed and arranged that 90 the lead will be rotated only during its axial movement in one direction.

11. In a pencil or like holder of the type referred to, the combination of sharpening members in the form of chisel-edge cutters 95 arranged about the lead near the forward end of the holder, a lead-carrier slidably arranged in the holder and controlled by a spring in such manner as to permit of the lead being moved inwardly between the sharpening members against the action of said spring by the application of pressure to the point of the lead and being moved outwardly between said members by the spring when the pressure is released, and means for pressing said sharpening members inwards sufficiently to grip 100 the lead locking it in its operative position.

12. In a pencil or like holder of the type referred to, the combination of sharpening members in the form of chisel-edge cutters 110 arranged about the lead near the forward end of the holder, a spring-controlled lead-carrier slidably arranged in the holder and controlled by a spring in such manner as to permit of the lead being moved inwardly between the sharpening members against the action of said spring by the application of pressure to the point of the lead and being moved outwardly between said members by the spring 115 when the pressure is released, and a cap adapted to be moved longitudinally over the sharpening members and having a part which during such longitudinal movement presses the sharpening members inwardly on to the lead sufficiently to grip the latter and lock it in its 120 operative position.

13. In a pencil or like holder of the type referred to, the combination of sharpening members in the form of chisel-edge cutters arranged about the lead near the forward end 130

of the holder, a lead-carrier slidably arranged in the holder and controlled by a spring in such manner as to permit of the lead being moved inwardly between the sharpening members against the action of said spring by the application of pressure to the point of the lead and being moved outwardly between said members by the spring when the pressure is released, a spring-controlled cap that is slidably and rotatably mounted on the body part of the holder, which cap has a conical end portion arranged to press the sharpening members inwardly against the lead during the rearward sliding movements of said cap, and means to determine various positions of said cap, for the purpose specified.

14. In a pencil or like holder of the type referred to, the combination of sharpening members in the form of chisel-edge cutters arranged about the lead near the forward end of the holder, a spring-controlled lead-carrier slidably arranged in the holder and controlled by a spring in such manner as to permit of the

lead being moved inwardly between the sharpening members against the action of 25 said spring by the application of pressure to the point of the lead and being moved outwardly between said members by the spring when the pressure is released, a spring-controlled cap that is slidably and rotatably 30 mounted on the body part of the holder, which cap has a conical end portion arranged to press the sharpening members inwardly against the lead during the rearward sliding movements of said cap, a pin co-acting with 35 a slot in said cap to determine various positions of the cap, which slot comprises a main longitudinal portion, a transverse portion, and a second transverse portion connecting with a second longitudinal portion which extends from said second transverse portion to the rear end of the cap, for the purpose specified.

In testimony whereof I affix my signature.

GEORGE SKEFFINGTON MILNE GRIMMER.
